UNITED STATES PATENT OFFICE.

JOHN K. ROBINSON, OF CHICAGO, ILLINOIS.

DESIGN FOR A BRUSH.

SPECIFICATION forming part of Design No. 25,466, dated May 5, 1896.

Application filed April 7, 1896. Serial No. 586,605. Term of patent 14 years.

To all whom it may concern:

Be it known that I, JOHN K. ROBINSON, a citizen of the United States, residing at Chicago, in the county of Cook and State of Illinois, have invented and produced a new and original Design for Brushes, of which the following is a specification, reference being had to the accompanying drawings, in which—

Figure 1 is a side elevation of a brush embodying my design. Fig. 2 is a plan view of the same as viewed from the rear face or back. Fig. 3 is a similar view of the opposite face of the brush.

The leading features of my design consist of the brush-block curved inward at its sides and outward at its ends on its front face with the bristles radiating therefrom and terminating in a line extending parallel to the front face of the block.

A represents the brush-block, presenting in outline as viewed from the rear, as shown in Fig. 2, opposite sides curved inward, as at *a*, and ends squared, as at *b*. As viewed from the side, as in Fig. 1, the block presents a rear flat face *c* and a front face extending for

a portion of its length parallel to the rear face and joining the same at its ends by curves *d*. The bristles radiate from the front face of the block and as viewed from the side terminate in a line extending parallel to the face of the block at *e*. As viewed from the rear, as shown in Fig. 2, the bristles terminate at the ends in straight lines parallel with the squared ends of the block, as at *f*, and as viewed from the front, as shown in Fig. 3, the bristles present an outline straight at the ends, as at *g*, and curved inward between the ends, as at *h*.

Having thus described my invention, what I claim is—

The design for a brush substantially as herein shown and described.

In testimony whereof I have hereunto set my hand and affixed my seal, this 28th day of February, 1896, in the presence of two attesting witnesses.

J. K. ROBINSON. [L. S.]
